AERATION METHOD FOR ESTABLISHING GAS LIFT IN OIL WELLS

Filed July 18, 1927

Patented Dec. 17, 1929

UNITED STATES PATENT OFFICE

FRANCIS W. LAKE, OF WHITTIER, CALIFORNIA, ASSIGNOR TO UNION OIL COMPANY OF CALIFORNIA, OF LOS ANGELES, CALIFORNIA, A CORPORATION OF CALIFORNIA

AERATION METHOD FOR ESTABLISHING GAS LIFT IN OIL WELLS

Application filed July 18, 1927. Serial No. 206,680.

This invention relates to the so-called "gas lift" method of flowing deep wells, particularly oil wells, and has been designed to overcome the excess hydrostatic head of oil which ordinarily accumulates in such wells prior to starting gas lift and which ordinarily can be removed only by application of a gas pressure greater than that required for normal operation of gas lift.

Subject matter somewhat analogous to the present case and relating to other specific initiation methods, is disclosed and claimed in my companion applications, Serial Numbers 206,677 and 206,681.

Gas lift, as now commonly practiced, consists in passing gas under pressure into a well containing a flow tube, so that the gas passes around the lower end of the flow tube in a stream and in its passage atomizes the oil as fast as it is forced up to said tube end by the natural rock pressure in the well, the atomized oil being carried to the surface in the gas stream. The gas may be introduced either through the flow tube or through the casing, the atomized oil being discharged from the other of the two; however, it is preferred usually to introduce the gas into the casing and discharge the oil from the flow tube.

In attempting to establish normal gas lift in some wells where the gas is to be introduced into the casing, it is frequently found that there is great loss in pressure between the point of introduction of the gas and the point of contact of said gas with the body of the oil in the lower end of the casing. This loss in pressure may be due to any one or more of several causes. For example, said pressure loss may be due to the presence of a barren or low pressure sand open to the well, or to a casing which is so leaky as to allow the escape of gas in sufficient amounts to prevent the building up of a pressure sufficient to force out the head of oil. Again, the pressure drop may be due to friction, especially in the deeper wells where the casing weaves from side to side, thereby causing the flow tube to contact the casing or to approach the same so closely as to materially reduce the space between the tube and the casing at many points;

this is particularly true where the tube is large relative to the casing.

In many of such cases, the available gas pressure would be sufficient to establish gas lift upon application of pressure to the casing, if it were not for the conditions which induce the pressure drop and if the maximum pressure could be maintained. Under such conditions, however, the highest available gas pressure is insufficient to start gas lift through the flow tube by the application of pressure in the casing merely because of said pressure loss.

The object of the invention is to present a method for applying the gas pressure which will prevent losses of high pressure gas and will enable the discharge of the hydrostatic head standing in the flow tube and the initiation of gas lift regardless of whatever losses result from said causes.

To accomplish this result, it has been found possible to reverse the normal direction of gas flow into the well, that is, to flow the gas through the tube into the casing. Since the tube usually is intact and thereby prevents pressure loss by leakage, the gas pressure then is sufficient (due to absence of such leakage or other loss) to overcome the hydrostatic head standing in the lower end of the tube so as to expel the accumulated column of oil therefrom and cause a flow of gas under the lower end of the tube into the oil body within the casing in sufficient quantities to thoroughly aerate the oil and to atomize at least a portion thereof and carry the same upward and out through the casing vent. This operation may be, and usually is, continued until a sufficient quantity of the oil body has been discharged to eliminate the static head and to bring the oil level down to a point approximating the lower end of the tube so that upon directing the gas flow into the casing, normal gas lift up through the tube will commence. In clearing the well with the casing vented, since the pressure in the casing is actually much lower than that in the tube, leaks from the casing under this low pressure are insignificant as are those from the casing after the head has been eliminated and gas lift instituted.

Thus, the invention, generically stated comprises initiating gas lift in an oil well having a casing containing a body of accumulated oil into which a flow tube depends and wherein material pressure losses from the casing 5 are encountered due to casing leaks, open sands or the like, by applying gas to the flow tube under a pressure at least sufficient to force the oil out of the flow tube and to force 10 said gas up through the oil in the casing to aerate, atomize and discharge the oil from the casing, the direction of flow according to a preferred form being then reversed to maintain gas lift.

15 In the accompanying drawing wherein various steps in the operation of the method are diagrammatically represented:

Fig. 1 indicates the introduction of the gas through the flow tube to reduce the hydrostatic head in a leaky casing;

20 Fig. 2 represents the final establishment of gas lift up through the flow tube of Fig. 1, gas being introduced through the leaky casing after elimination of the oil head;

25 Fig. 3 indicates the introduction of gas through the flow tube to reduce the hydrostatic head in a well wherein the tube depends below the casing so that gas, if applied, to the casing, will be lost to the sands when the 30 oil level is depressed to the lower end of the casing; and

Fig. 4 indicates the establishment of normal gas lift up through the flow tube upon elimination of the hydrostatic head of Fig. 3.

35 In Fig. 1 there is represented a well having a leaky casing 10, the holes or perforated portions which account for the leaks being indicated at 11. Into this casing, the usual flow tube 12 depends and enters the oil body 40 which has accumulated therein and risen to the level 14. Valved connections 15 and 16 leading from a gas compressor "C" are respectively connected with the casing and the flow tube, so that gas under pressure may 45 be applied to either. A valve controlled oil and gas outlet 18 is also provided on the casing. In this instance, when gas is applied through the connection 15 to the casing for the purpose of depressing the oil level, the 50 outlet 18 being closed, so much pressure is lost through the leaky portions 11 that the resultant pressure is insufficient to force over the oil head and cause gas lift to be established through the flow tube. However, by 55 opening the outlet 18 and introducing the gas under pressure through the flow tube, the full pressure of the gas is made available and succeeds in overcoming the head in the tube so as to expel the oil therefrom and 60 cause the gas to flow upward through the oil body. The introduction of gas is then continued in sufficient quantities to atomize the oil and carry the same upward and outward through outlet 18, and ordinarily this 65 is continued until the oil level has been

lowered to the bottom of the flow tube as indicated at 20 in Fig. 2. Inasmuch as the casing is vented under this condition, the loss of gas through the leaky portion 11 under the reduced pressure in the casing is not appreciable. If desired, the flow of the well in this direction may be continued. However, ordinarily the flow of gas is reversed upon proper depression of the level by introducing the gas through connection 15 and expelling the oil from the top of the tube 12 as indicated in Fig. 2. Since the gas pressure now required to flow the well (that is by atomizing the oil,) is much less than that required to expel the head, the loss of gas through the leaky portions becomes relatively insignificant.

Sometimes the condition represented in Fig. 3 exists wherein the flow tube depends to a point opposite the sands. In this instance, if pressure is applied in the casing, part of the same is lost into the sands as soon as the oil level has been depressed to the upper limit of the oil bearing stratum. However, the gas may be introduced through the tube 12 and allowed to flow around the lower end thereof and up through the oil body thereby atomizing the latter and discharging the same from the casing in the same manner as described above, and the direction of the introduction of gas reversed, if desired, when the oil level has been reduced to the lower end of said tube, as indicated in Fig. 4.

During the aeration step, the body of oil is so thoroughly charged with gas, both by absorption and by mechanical entrainment, that upon restoration of the normal direction of flow such entrained gas will, by expansion, materially assist the establishment of the gas lift operation. In fact, this advantage is so evident that it is not always necessary to lower the oil body to the end of the flow tube by the atomizing effect. It is to be understood that this method of establishing reverse flow and then establishing normal flow, may constitute the entire method of initiating gas lift, or it may constitute only the final steps thereof. For example, it is possible to employ as an initial step other methods for charging the oil body with gas, and after such preliminary steps have been taken, reverse-flow can be more quickly established by reason of the lightened condition attained in the oil body by the absorption and entrainment of gas.

It is to be understood, of course, that after reverse flow is once established, that is, by passing gas through the tubing into the casing and flowing out through the casing, gas lift may be continued in such reverse direction, if desired, since it is not always necessary to return to the normal flow upward through the tubing. In any event the major purpose of the invention is the introduction of gas into the oil body in sufficient quan-

ties and for a sufficient length of time to thoroughly liven up and remove an appreciable part of the heavy head of dead oil which stands in the well and which requires to be removed before normal gas lift can be established. The method may be considered to have been completed when gas lift is established either through the tubing or through the casing, whereupon a lower pressure ordinarily can be resorted to for continuing gas lift.

It is preferred always to use natural gas due to its stability and safety, but air or other gas may be used if desirable. The introduction 15 of gas under pressure by means of the compressor "C" may be replaced with gas from an adjacent well in any case where gas under a sufficiently high pressure may be so obtained, the control of such introduction 20 being managed in the same fashion as above described.

As an example of one method of practicing the invention, in an instance where loss from the casing was so great that pressure therein 25 could not be built up above 300 #, a pressure of 500 # was applied to the tube. This was sufficient to force the oil out of the tube and establish gas lift up through the casing until the oil head was removed, whereupon 30 the gas was reversed to flow up through the tube and the pressure was dropped to 175 # to continue gas lift.

The above disclosures are to be considered not as limiting but as merely illustrative, and 35 many variations of the invention may be made within the scope of the following claims.

I claim:

1. A method for gas lift in an oil well having a casing and tube depending thereinto, comprising introducing gas under pressure to one of said members for atomizing and discharging oil from the other, and then reversing the gas flow to establish normal gas lift 45 operation in the opposite direction.

2. A method for gas lift in an oil well containing a well casing and a flow tube depending thereinto, wherein it is desired to establish gas lift for discharging oil from the 50 top of the flow tube, comprising introducing gas under pressure into the flow tube and causing it to pass beneath the lower end of the flow tube into the oil body within the casing and to atomize a portion of said oil body and discharge the same from the casing, continuing such operation until the oil level 55 has dropped to a point to insure normal gas lift, and reversing the gas flow by introduction of gas into the casing and under the lower end of the flow tube whereby the oil is atomized in the flow tube and discharged therefrom thus establishing normal operation.

3. A method for gas lift in an oil well containing a casing and a depending flow tube,

comprising introducing gas under pressure in a direction opposite to that in which it is desired to establish normal flow, causing said gas to pass beneath the lower end of the flow tube and upward through the oil body 70 to charge the same with gas and atomize a portion thereof, continuing the flow to discharge a portion of said oil body, and then reversing the gas flow to cause it to pass in the opposite direction under the lower end 75 of said flow tube and establish normal gas lift operation.

4. In a method for initiating gas lift in an oil well containing a casing in which a body of oil has accumulated and within which a flow tube depends into the oil, and where there is a material pressure loss from the casing, the steps of passing gas into the flow tube under pressure which is sufficient normally to overcome the hydrostatic head of oil in the tube, but insufficient to overcome 80 said head and said pressure loss combined, and flowing said gas from the lower end of the tube into the oil body in the casing to charge the same with gas.

5. A method according to claim 4 wherein gas flow is continued to an extent to atomize a portion of the oil body and discharge it from the casing to lower the oil level therein.

6. A method for initiating gas lift in an oil well having a casing from which material pressure losses are encountered and wherein a flow tube depends into a body of oil accumulated in the well, comprising applying gas to the flow tube under a pressure sufficient to force the oil standing therein out of the flow tube and forcing said gas up through the oil in the casing to atomize and discharge the same from the casing to lower the oil level to a point approximating the lower end of 100 the flow tube, and then reversing the direction of gas flow.

7. In a method according to claim 4 the additional steps of continuing gas flow to an extent to atomize a portion of the oil body and discharge it from the casing to cause the oil level therein to drop, and then reversing the gas flow to cause it to pass in the opposite direction and establish normal gas lift.

Signed at Los Angeles, in the county of 110 Los Angeles and State of California, this 12th day of July, A. D. 1927.
